UNITED STATES PATENT OFFICE.

VICENTE RUIZ, OF NEW YORK, N. Y., ASSIGNOR OF ONE-HALF TO CECILIO VELASCO, OF RIOJA, SPAIN.

PROTECTOR FOR CUES.

1,262,262.

Specification of Letters Patent.

Patented Apr. 9, 1918.

Application filed October 16, 1917. Serial No. 196,875.

To all whom it may concern:

Be it known that I, VICENTE RUIZ, a citizen of the United States, residing at New York, in the county of New York and State 5 of New York, have invented certain new and useful Improvements in Protectors for Cues, of which the following is a specification.

My invention is a sanitary protector for use upon a billiard cue.

10 An important object of the invention is to provide means of the above mentioned character, which may be manufactured so cheaply that after the same has been used by a single player it may be removed and 15 discarded, and a fresh or new protector placed upon the cue.

A further object of the invention is to provide means of the above mentioned character, adapted to be held securely upon the 20 cue without longitudinal slipping, and having its surface corrugated or roughened, for providing a convenient grip.

Other objects and advantages of the invention will be apparent during the course 25 of the following description.

In the accompanying drawings forming a part of this specification and in which like numerals are employed to designate like parts through the same,

30 Figure 1 is a side elevation of a billiard cue, having my device applied thereto,

Fig. 2 is a perspective view of the device, and,

Fig. 3 is an enlarged fragmentary trans- 35 verse section through the device.

In the drawings, wherein for the purpose of illustration is shown a preferred embodiment of my invention, the numeral 5 designates a billiard cue of any well known or 40 preferred construction. This cue tapers longitudinally and increases in diameter rearwardly, as shown.

My sanitary protector is in the form of a tube or sleeve 6 which is preferably formed 45 of paper, while other suitable material may be employed. This tube or sleeve tapers longitudinally and increases in diameter rearwardly, for corresponding to the taper of the cue.

50 As clearly shown in Fig. 3, the tube 6 is provided with outwardly bulging portions or projections 7, which are forced or bent from the material thereof.

In the use of the protector, the same is passed over the small end of the cue and 55 moved rearwardly upon the enlarged rear end thereof, and securely clamped to the cue by proper longitudinal movement. It will be found that the tubular protector or sleeve will not slip upon the cue. As shown 60 in Fig. 1, the protector is arranged upon that portion of the cue which is permanently held in the hand of the player, and the hand is thereby prevented from contacting with the cue. The extensions or 65 lugs 7 form a corrugated or roughened surface thereby keeping the hand from slipping upon the protector.

I have found that the device may be advantageously formed of paper or similar 70 material and the same may be manufactured and sold at a small cost, such as a cent apiece. After each player has finished with the cue, the used protector is removed therefrom and a new or fresh protector 75 placed thereon before the cue is again used.

It is to be understood that the form of my invention herewith shown and described is to be taken as a preferred example of the same, and that various changes in the shape, 80 size, and arrangement of parts may be resorted to without departing from the spirit of the invention or the scope of the subjoined claims.

Having thus described my invention, I 85 claim:

1. As an article of manufacture, a sanitary protector for cues, comprising a tapered paper sleeve adapted to be detachably arranged upon the cue to prevent the 90 hand from contacting with the cue and to be removed therefrom when soiled.

2. As an article of manufacture, a sanitary protector for cues, comprising a paper sleeve adapted to be detachably arranged 95 upon the cue to prevent the hand from contacting with the cue and to be removed therefrom when soiled, said sleeve having portions of its material at spaced points forced outwardly for providing projections 100 which prevent slipping of the hand upon the sleeve.

In testimony whereof I affix my signature.

VICENTE RUIZ.
